SINK PARTITION INSERT

Seoris M. Moyes, Stockton, Calif., assignor of two-fifths to Eugene M. Stagnaro, Stockton, Calif.

Application March 23, 1936, Serial No. 70,282

2 Claims. (Cl. 4—183)

My invention relates to improvements in a sink partition insert and more particularly to the adjustable type which may be used for the purpose of dividing a sink into several compartments.

5 The principal object of my invention is to provide an improved sink partition insert of the kind described herein which can be adapted to the conventional type of kitchen sink and when thus used providing a means of rapidly converting a single 10 compartment sink into a plurality of compartments.

Another object of my invention is to provide an improved sink partition insert of the kind described which due to its particular construction 15 provides a water tight joint where the sink partition insert intersects the surface of the walls and bottom of the sink.

Other objects of my invention are constructive features which make it simple, compact, durable, 20 economical, convenient, efficient and satisfactory for use wherever found applicable.

Many other objects and advantages of the construction herein shown and described will be obvious to those skilled in the art from the 25 disclosures herein given.

To this end my invention consists in the novel construction, arrangement and combination of parts herein shown and described and more particularly pointed out in the claims.

30 In the drawing wherein like reference characters indicate like or corresponding parts.

Fig. 1 is a plan view of the device as applied to a kitchen sink.

Fig. 2 is a cross section taken therethrough.

35 Fig. 3 is a longitudinal section view therethrough.

Fig. 4 is an enlarged part sectional view.

Fig. 5 is an enlarged part longitudinal sectional view.

40 Fig. 6 is an enlarged end elevation.

In the drawing wherein I have illustrated the preferred embodiment of my invention, 1 indicates the conventional sink, 2 sink framing, 3 sink splash board, 4 sink apron, 5 sink drain, 6 sink outlet, 7 sink partition insert, 8 compartment formed by the insertion of the sink partition insert 7, 9 indicates liquid in compartments 8.

The sink partition insert 7 is composed of the horizontal member 10 and the wall 11. The contact of the wall 11 with the sink bottom and side walls is made through flexible flanges 12.

It will be noted that the flexible flanges 12 are so constructed that a space 13 is formed between them and the interior faces of the sink 1. In the construction of the device this space can extend the full length of the flexible flanges, or 5 this space may only take part of the length of the flexible flange.

In the placing of the improved sink partition insert, the device is inserted down into the sink, with sufficient force which will expel the air from 10 the space 13. It is obvious that this forms a vacuum causing the flexible flanges 12 to make a water tight joint where they contact the surface of the sink. When the sink compartments are full of water, this pressure is transmitted to 15 the flexible flanges 12 which helps the flanges 12 to make a water tight joint due to the hydrostatic pressure.

From the foregoing it will be seen that this device embodies several novel features in construction 20 in providing an efficient improved sink partition insert.

Having thus described my invention, it is obvious that various immaterial modifications may be made in the same without departing from the 25 spirit of my invention; hence I do not wish to be understood as limiting myself to the exact form, construction, arrangement and combination of parts herein shown and described or uses mentioned.

What I claim as new and useful and desire to 30 secure by Letters Patent is:

1. An improved sink partition insert comprising a partition wall member with a flexible flange in contact with the sink walls, the aforesaid 35 flange being concave, which forms a cavity between the outer contact edges of the flange, thus forming a means of making a water tight joint by the formation of a vacuum between the flange edges upon pressing the insert into position. 40

2. An improved sink partition insert comprising a partition wall member with a flexible flange in contact with the sink walls the aforesaid flange being concave, which forms a cavity between the outer contact points of the flange, thus forming a 45 means of making a water tight joint by the formation of a vacuum between flange edges upon pressing the insert into position, and a top reinforcing member for stiffening the sink partition.

50 SEORIS M. MOYES.
